INVENTOR:
Cyrus S. Hood,

UNITED STATES PATENT OFFICE.

CYRUS S. HOOD, OF CORNING, NEW YORK.

REGISTER.

SPECIFICATION forming part of Letters Patent No. 465,561, dated December 22, 1891.

Application filed March 2, 1891. Serial No. 383,416. (No model.)

To all whom it may concern:

Be it known that I, CYRUS S. HOOD, a citizen of the United States, residing at Corning, in the county of Steuben and State of New York, have invented certain new and useful Improvements in Registers; and I do hereby declare the following to be a full, clear, and exact description of the invention, such as will enable others skilled in the art to which it appertains to make and use the same.

Prior to my invention floor-registers as ordinarily constructed have been provided with a rectangular surface plate consisting of central fret-work or open-work and an adjacent border surrounding the open-work and connected thereto at short intervals. The necessary consequence of this multiplicity of connecting points between the two has been that the heat imparted to the fret-work (which is interposed directly in the rising current of heated air) is transmitted at once by conduction to the outlying border, which would otherwise be but slightly affected by the passage of the heated air. As this border rests upon or against the floor-carpet, danger of scorching or igniting the latter is to be apprehended from air-currents of intense heat, the production of which cannot always be guarded against.

One of the objects of my invention is to practically eliminate this source of danger by lessening the number of connecting-points between the fret-work and border, while at the same time providing that the fewer connections employed shall be of such character as to make the union between the two none the less stable, strong, and durable. To this end in casting the surface plate I provide that the fret-work shall only be connected with the border at or near the inner angles or corners of the latter, but by means of flanges, which, extending from a downwardly-projecting rim of the border, connect with the lower surface of the fret-work, terminating at a short distance from the angle in a gradual taper, as will more fully appear from the fuller detailed description hereinafter given.

In the ordinary construction of floor-registers another disadvantage (which my invention is designed to remove) is that the floor-carpet cannot be taken up without lifting out or removing in addition to the surface plate the

tin box-casing beneath it which is secured to the under side of the border, and with which the hot-air pipe from the furnace connects. 55 The lifting out of this casing breaks the joint with the hot-air pipe, which joint frequently cannot be satisfactorily re-established except by a skilled workman, and, moreover, leaves the floor-opening in such condition that the 60 cellar-gases can escape upwardly through it, hastened by the exhaust action of the hot-air current. This undesirable condition of affairs I completely obviate by a construction permitting the removal of the surface plate 65 without disturbing in any way the casing beneath it or the joint between such casing and the hot-air pipe. As incidental to this construction I impart to the interior of the casing a form or configuration presenting practically no lodging-place for the accumulating of thick deposits of dust—a fault present in the usual rectangular box-casings. I take additional precautions, moreover, against danger from conflagration by providing the 75 casing with stud projections extending from its edge and projecting into the flooring, said stud projections serving as the only means for supporting the casing, whereby a free space is left almost entirely around the upper edge of the casing between it and the flooring, correspondingly diminishing the conduction of heat from the one to the other. To reduce the danger from fire to a still greater degree, I interpose between the carpet and the 85 under face of the border portion of the surface plate a strip of asbestos paper or its equivalent, and this strip I continue as a packing for the flange and recess joint between the casing and the downwardly-projecting rim, heretofore referred to, of the border-plate. The strip thereby subserves the double purpose of an additional safeguard against fire and to effectually prevent the drawing in 90 of cellar-gases at the joint in question. 95

In the accompanying drawings, forming a part of this specification, Figure 1 represents a central cross-section of a floor-register and its appurtenances embodying my invention. Fig. 2 represents, on a larger scale, a bottom 100 view of a corner of the surface plate of the register, said corner being represented as slightly tilted backward in order to more fully show its construction. Fig. 3 represents a top

plan view of the register, and Fig. 4 represents a top plan view of the casing and illustrates the manner of supporting it from the flooring.

5 Similar letters of reference indicate similar parts throughout the several views.

Referring to the drawings, A indicates a floor, and *a* the carpet thereof, said floor being cut away, as shown, to accommodate the 10 floor-register. The floor-register consists, primarily, of two parts—an upper surface plate and a lower casing B, said casing being connected to the hot-air pipe or furnace-pipe C and having the usual dampers *e*. It will be 15 noted that the casing B is of less width and length than the floor-opening, from which it is separated by an intervening space spanned only by the projecting studs or lugs *b*, which project into the flooring, thereby sufficiently 20 supporting the casing, but leaving its main body portion out of actual contact with the wood. The casing tapers gradually toward the oblong elliptical opening through which the hot-air pipe C passes, thereby presenting 25 the advantage of leaving no corners or angles to serve as lodging-places for the accumulation of dust deposits, and also permitting an ordinary round pipe of proper dimensions to be readily fitted within said opening so as 30 to completely fill the same.

The upper edge of the casing B is provided with a groove *n*, as shown, for the reception of the downwardly-projecting rim-flange *d* of the surface plate, and in order to insure a tight fit 35 between the said groove and rim a packing *m* is interposed between the two. Said packing is preferably of asbestos cloth or like non-inflammable material, which is a poor conductor of heat and yet sufficiently dense to 40 prevent the passage of the cellar-gases through the joint. It is continued, as shown, so as to extend between the carpet *a* and the border *f* of the surface plate, thereby largely protecting the carpet from the heat of the said 45 border.

To prevent the border itself from being unduly heated is, as I have heretofore explained, one of the main objects of my invention, and to this end the connection between said border 50 and the central fret-work *r* is made by means of deep flanges *s* at or near the corner-angles, the fret-work being otherwise disconnected from the border. This arrangement reduces the conduction of heat from the fret-work to the border to a minimum, while the flanges *s*, by reason of their depth and because of the fact that they extend for a short 55 distance beneath the fret-work, as shown, furnish a reliable supporting connection for the latter.

The preferable location for the supporting-flanges *s* is at or substantially at the corner-angles. It is obvious, however, that instead of being located at the corners they may be 60 placed at a greater or less distance therefrom and still preserve their characteristic function.

Having thus described my invention, what I claim, and desire to secure by Letters Patent of the United States, is—

1. In a register, the combination, with the central fret-work, of a surrounding border, a downwardly-projecting rim from said border, and supporting-flanges extending downwardly from the fret-work and connecting it 70 to the rim, the fret-work being otherwise separated from the border by an intervening free space, substantially as described.

2. In a register, the combination, with the central fret-work, of a surrounding border, a downwardly-projecting rim from said border, and supporting-flanges located at the corner-angles and extending downwardly from the fret-work and connecting it to the rim, the fret-work being otherwise separated from the 80 border by an intervening free space, substantially as described.

3. In a register, the combination, with the central fret-work, of a surrounding border, a downwardly-projecting rim from said border, 90 and supporting-flanges extending inwardly beneath the fret-work and downwardly from the fret-work to the rim, the fret-work being otherwise separated from the border by an intervening free space, substantially as de- 95 scribed.

4. In a register, the combination, with the surface plate having an outlying supporting border-flange and a downwardly-projecting rim, of a subjacent casing supported directly 100 from the flooring and connected to the hot-air pipe, said casing being provided with a groove or shoulder for the reception of said rim, substantially as described.

5. In a register, the combination, with the 105 surface plate having a downwardly-projecting rim, of a subjacent casing supported from the flooring and connected to the hot-air pipe, said casing being provided with a groove or shoulder for the reception of said rim, and 110 a packing for the joint thus formed, substantially as described.

6. In a register, the combination, with the surface plate having a downwardly-projecting rim, of a subjacent casing supported from the 115 flooring and connected to the hot-air pipe, said casing being provided with a groove or shoulder for the reception of said rim, and a packing for the joint thus formed, the packing consisting of a flexible non-inflammable 120 strip continued outwardly beneath the border of the surface plate, substantially as described.

7. A register having a surface plate and subjacent casing, the main body portion of 125 said casing being separated from the flooring by an intervening space, but having lugs or studs for supporting it from said flooring, substantially as described.

8. A register having a rectangular surface 130 plate and subjacent casing, said casing tapering downwardly toward and terminating in a central elliptical opening, substantially as described.

9. A register consisting of a surface plate having a central fret-work and an outlying border having a dependent rim, the said fret-work and rim being connected by deep corner-
5 flanges extending beneath the fret-work, in combination with a subjacent casing having a groove or shoulder for the reception of the rim and having lugs for supporting it from the flooring, said casing tapering downwardly

10 to and terminating in a central elliptical opening, substantially as described.

10. In a register, the combination of a surface plate and a subjacent casing, the sides of the latter being separated from the floor-
15 ing by an intervening free space and having outwardly-projecting lugs at its upper edge for supporting it from the floor, substantially as described.

11. In a register, the combination of a rect-
20 angular surface plate having a downwardly-projecting rim, and a subjacent casing having

a shoulder for the reception of the rim, said casing tapering downwardly from the inner edge of the shoulder and terminating in an elliptical central opening, substantially as de- 25 scribed.

12. In a register, the combination of a surface plate having a downwardly-projecting rim, and a subjacent casing having an internal flange or shoulder for the reception of the 30 rim, the casing having outwardly-projecting lugs at its upper edge for supporting it from the floor and the sides of the casing being separated from the flooring by an intervening free space, substantially as described. 35

In testimony whereof I affix my signature in presence of two witnesses.
